UNITED STATES PATENT OFFICE.

REMIGIUS SCHAEFER, OF NEW YORK, N. Y.

VENT-BUNG.

SPECIFICATION forming part of Letters Patent No. 515,095, dated February 20, 1894.

Application filed December 7, 1893. Serial No. 492,966. (No model.)

To all whom it may concern:

Be it known that I, REMIGIUS SCHAEFER, a citizen of the United States, residing in the city, county, and State of New York, have invented certain new and useful Improvements in Vent-Bungs, of which the following is a specification.

This invention relates to an improved vent-bung, which is intended mainly for the purpose of drawing off still liquids, such as wines of all kinds, whiskies, &c., from the casks in which they are stored, without the necessity of drawing the contents of a large cask into a small cask, the vent-bung preventing the formation of fungi and turbidity in the liquids, as the air that is drawn in through the vent-bung is purified of all impurities and saturated with alcoholic vapors, which tend to keep an atmosphere of antiseptic character above the body of wine in the cask or barrel.

The invention consists of a vent-bung which is composed of a receptacle provided with a suitable lining and a central vent-tube, a tightly fitting cap that is screwed into the main part or receptacle, and a vent-tube provided with a stop-cock which extends from the upper part to near the bottom of the receptacle, as will be fully described herein-after and finally pointed out in the claims.

In the accompanying drawings, Figure 1 represents a vertical longitudinal section of a cask, filled with a still liquid, such as a Rhine wine or other still wines and provided with my improved vent-bung. Fig. 2 is a vertical transverse section of my improved vent-bung drawn on a larger scale, and Figs. 3 and 4 are horizontal sections respectively, on line 3—3, and 4—4 of Fig. 2.

Similar letters of reference indicate like parts in all the figures.

Referring to the drawings, A represents the main piece of my improved vent-bung, which is made in the nature of a hollow receptacle that is provided at its interior with a suitable lining *a* of sheet-metal and a solid bottom plug *a'*. The lining is provided at its upper end with a shoulder *a²* and an interior screw-thread *a³* for allowing the closing of the main-piece or receptacle A, by means of a cap B, which forms the head of the vent-bung and through the medium of which the same is driven into the bung-hole of the cask.

Between the threaded lower part of the cap B and the shoulder *a²* of the lining *a*, as well as between the upper edge of the receptacle A and the cap B are respectively interposed elastic gaskets *b b'*, of leather or other suitable material, which serve to produce the hermetical sealing of the receptacle, so that no air can pass into the same.

In the bottom *a'* of the receptacle A is screwed a vent-pipe C which communicates with a bore C' in the lower part of the receptacle A, so as to establish the connection between the interior of the receptacle and the cask. A second vent-tube D extends from a point near the upper part of the receptacle to near the bottom of the same, the upper end being connected with a pipe D' that passes through the outside of the same, its outer end being provided with a stop-cock D² as shown clearly in Fig. 2. The connection between the pipe D' and the receptacle is made in an air-tight manner. The interior of the hollow receptacle A is filled with alcohol or any other suitable antiseptic liquid, such as a solution of salicylic acid, care being taken that the level of the liquid does not rise above the level of the upper end of the vent-tube D'.

My improved vent-bung is used as follows:—When it is driven into a cask, the contents of which are to be drawn off at different times, it is driven tightly in the bung-hole and the stop-cock D² of the vent-tube D is set to permit air to enter into the interior of the bung. As soon as the faucet P is opened and the liquid drawn from the cask, the air is drawn in through the vent-tube D and compelled to percolate through the body of alcohol or other antiseptic liquid in the receptacle, so as to be purified of all adhering bacilli or micro-organisms, it being then conducted through the central vent-tube C to the interior of the cask. In its passage through the antiseptic solution in the receptacle A, the air carries along some of the vapors of the same so as to fill the space above the liquid in the cask with a mixture of atmospheric air and alcoholic vapors, which prevents the formation of any fungi on the surface of the liquid in the cask. As the cask is gradually drawn off, the level of the liquid in the same is lowered and the space

above filled with the before-described mixture of air and vapors. Owing to the anti-septic character of these vapors, it is not necessary to draw off the entire body of air from the cask and transfer it into another smaller cask as has been practiced in the wine trade before. When the required quantity of liquid is drawn off, the faucet is closed and also the stop-cock of the vent-tube D, so that no air can pass into the cask, whereby the liquid in the same is only placed in contact with the mixture of air and antiseptic vapors collected in the empty space above the liquid.

By the use of my improved vent-bung, the entire body of liquid in the casks can be drawn off without any deterioration of the liquid or formation of fungi on the same. The vent-bung serves therefore, as an important and time saving device for beers, Rhine wines and other still wines, as it dispenses with the arduous labor of transferring the contents of a partly emptied cask into smaller casks.

Having thus described my invention, I claim as new, and desire to secure by Letters Patent—

1. A vent-bung, consisting of a main wooden body forming a receptacle, a screw-threaded

metallic lining fitting tightly therein, a screw-threaded cap for engaging the screw-threads of said lining, a vent-tube in said receptacle, passing through the body of the same, and a second vent-tube extending to near the bottom of the receptacle and passing through the same to the outside, being provided with a stop-cock at its outer end, substantially as set forth.

2. A vent-bung, consisting of a main-body forming a receptacle, a shouldered lining fitting tightly therein, a cap adapted to be screwed into the upper end of the lining, a gasket interposed between the cap and the shoulder of the lining, a vent-tube in said receptacle, passing through the body of the same, and a second vent-tube extending to near the bottom of the receptacle and passing through the same to the outside, being provided with a stop-cock at its outer end, substantially as set forth.

In testimony that I claim the foregoing as my invention I have signed my name in presence of two subscribing witnesses.

REMIGIUS SCHAEFER.
